UNITED STATES PATENT OFFICE.

GEORGE G. MEVI, OF MOUNT KISCO, NEW YORK.

HAND STAMP.

Application filed July 2, 1924. Serial No. 723,785.

The object of this invention is to increase the utility of hand stamps by improvements made therein, the improvements having reference to several important parts of the device and being of a nature such as to overcome disadvantages which are inherent in hand stamps hitherto proposed. The invention, therefore, consists in certain peculiarities in the construction of parts and in certain novel combinations and correlations of elements substantially as hereinafter described and particularly pointed out in the appended claims.

In the accompanying drawings, I have illustrated the preferred embodiment of the invention, but it should be understood that the embodiment is exemplary and that changes in the details may be made without departing from the spirit of the invention. 20 In said drawings, wherein like characters of reference denote corresponding parts in the several views.

Fig. 1 is a plan view of the stamping element on a very large scale, the scale being about three times the size of the element, in actual practice;

Fig. 2 is a longitudinal section on the irregular line 2—2 of Fig. 1;

Fig. 3 is a cross section on the line 3—3 of Fig. 1;

Fig. 4 is a plan view of the blank from which the container portion of the stamping element is formed, showing the same on a smaller scale than the preceding figures;

Fig. 5 is a view in elevation showing the stamping element applied to a support, a portion only of the latter being illustrated;

Fig. 6 is a detail perspective view of the element of the support which receives the stamping element;

Fig. 7 is a sectional view through a drum employed as a support for a series of the stamping elements, showing two of the receivers, one supplied with a stamping element and the other empty;

Fig. 8 is a view of one of the end members of said drum;

Fig. 9 is a longitudinal sectional view of a hand stamp which embodies the said drum, a series of the stamping elements and a series of receivers for said stamping elements, together with an indicating means, an inking means, an operating handle, and appropriate connections, the parts being so correlated that rotation of the operating handle will ro-

tate the printing drum to bring a selected stamping element into position for an impression and will indicate when said position has been reached by said stamping element, and longitudinal movement of said handle will cause ink to be applied to the selected stamping element and also move the drum bodily and cause said stamping element to make its impression;

Fig. 10 is a vertical sectional view on the irregular line 10—10 of Fig. 9, but showing the parts in the positions they occupy while the impression is being made;

Fig. 11 is an end elevation of the hand stamp, but omitting the handle portion of the operating means and the indicating means, and showing in dotted outline the stamping drum, inking means and adjunctive parts in the positions they occupy when not in use;

Fig. 12 is a top plan view of the hand stamp with the operating handle omitted; and

Fig. 13 is a detail view of one of the indicators.

The stamping element hereinafter called "stamp" is composed of two members, to wit, a type member A and a container A' therefor, secured together to form a unitary structure. The type member is a sheet block or the like, formed of soft rubber or other suitable material and having one or more type characters *a* thereon. The container A' is preferably composed of sheet metal stamped up into shape from a blank such as is shown in Fig. 4. This blank comprises a body *a'* whose longitudinal edges are serrated as shown at *a''* and whose lateral edges, or ends, are formed respectively to provide a lip or flange *a'* at one end of the blank and lips or flanges *a*³ and *a*⁴ projecting one from the other, at the other end of the blank.

In the production of the container A' from this blank the body of the blank is folded inward along the longitudinal lines 5 at opposite sides thereof and bent inwardly along the lines 6, (Fig. 4); thereby forming marginal horizontal flanges 10 extending longitudinally of the frame and arranged outwardly of side flanges 11 which rise from the inner upper surfaces of the marginal flanges 10 (Fig. 3). It will be noted that since the horizontal, marginal, flanges 10 are produced substantially by

bending the portions of the blank at the opposite longitudinal sides thereof between the lines 5 and 6 inward upon the body of said blank, the outer longitudinal edges of the flanges will be along the lines 5 and hence in line with the side edges of the lip or flange a^2 , so that when said lip or flange is bent upward along the line 7 it will not only close one end of the space between the side flanges 11 but will also extend beyond said flanges to the outer edges of the marginal flanges 10 and thereby form stops 12 arranged outward of said side flanges and at one end of each of the respective marginal flanges 10.

In short, the construction described provides a container which is closed at the bottom and open at the top and comprises side walls 11, marginal longitudinal flanges 10 and an end wall whose ends form stops 12 at one end of both said marginal flanges and whose intermediate portion closes the space between the side wall 11; and also includes a lip or flange a^2 at the end opposite the stops 12.

In the space defined longitudinally by the side walls 11 and at one end by the portion 13 of the end wall, the type member A is arranged and this type member is held in position within the container A' by bending the upper portions of the side flanges 11 and by bending the lip or flange a^2 , over upon the upper surface of the type member, and further by bending the serrated or toothed portions of the side flanges 11 downward into the body of the type member. Although the bottom of the container has been described as closed it will, of course, be understood that it is only necessary in practice that it be of a construction which will co-operate with the upper flanges or lips in assuring the retention of the type member A.

The stamping member thus described is of simple and very durable construction. It may be kept in stock for an indefinite time without deterioration and will last a long time in use. Moreover, its construction is such that it may be used upon any hand stamp or the like of any type or style having an appropriate supporting member for the printing element. A suitable supporting member for the stamping element would be one comprising channels or grooves to receive the marginal flanges 10 and ledges which overhang said flanges, together with surfaces to be engaged by the stops 12 and the lip a^2 , respectively: whereby the stamping element may be applied by sliding it longitudinally to its place and will be held securely against accidental displacement by turning the lip a^2 into holding relationship with the part of the supporting member with which it is to co-operate for the purpose. The type member A may be con-

structed of soft rubber having a thickness such as to fill the container A'; or it may be made of a plurality of layers of rubber, the lower or foundation layer being separate from the upper or type carrying layer and being of sponge rubber, for example. I prefer, in practice, however, that its type-carrying portion be a comparatively thin layer of soft rubber and that there be interposed between this layer and the bottom of the container, one or more layers of paper or the like, such as blotting paper, as indicated in Figs. 2 and 3, in which the type-carrying layer is marked α and the other layers are marked α' .

Whatever the style of hand stamp to which the described stamping element is applied, I prefer to employ a receiver and retainer of substantially the form shown in Fig. 6, for said stamping element. This receiver and retainer, marked B as a whole, has an upwardly open body, open also at its ends, having side walls 14 with flanges 15 which extend toward each other from the outer ends of the side walls 14. It will be apparent that the stamping element may be slid longitudinally into its place upon said receiver and retainer, and will be firmly held against longitudinal movement in one direction by the co-operative action of its stops 12 and the contiguous ends of the side walls 14 and in the other direction by bending its lip a^2 over against the adjacent end of the receiver and retainer: and also held firmly against lateral movement and against movement in a plane at right angles to its longitudinal and lateral movements by the co-operative action of the marginal flanges 10 of the stamping element and the walls 14 and flanges 15 of the receiver and retainer.

It will be noticed that the stamping element may be removed with the same ease and facility with which it may be applied, its removal necessitating only the bending of its lip a^2 out of holding relationship with the part with which it co-operates and then slipping the stamping element out of its receiver and retainer, i. e., out of the part, of whatever suitable construction employed, which receives and holds it in operative relationship with its support. Interchange of the stamping elements, therefore, is easily and expeditiously accomplished.

I have illustrated the application of the stamping element to a hand stamp of the type which includes a rotative and bodily movable drum C carrying several of these stamping elements arranged around the periphery of the drum, the drum with its said stamping elements being correlated with means whereby any one of the stamping elements may be brought into position to make an imprint when moved bodily for the purpose of making such an imprint. The structure of this drum constitutes a second im-

portant part of the invention, it being particularly noticeable that the receiving and retaining element B forms an important member entering into the construction of said drum. In fact, although it may be useful in other types of hand stamps than those embodying a drum of this character, it was specially designed for its utility as a member of a drum of the construction now to be described, attention being called in this connection to the flanges or lips 16 and 17 at its opposite ends. This drum C comprises two opposite end members 20 and 21 having outwardly extending flanges 22 and 23 connected with each other by a series of the elements B, which substantially form the periphery of the drum and have their lips or flanges 16 and 17 bent into a holding relationship with the flanges 22 and 23. The members 20 and 21 and also the elements B are preferably made of sheet metal stamped to shape and when assembled form a drum to receive a number of the stamping elements A, one of which stamping elements is, as will be apparent, inserted in each element B.

A filler member 25, which may be of wood, is preferably employed to give strength and rigidity to the drum. Each end member 20, 21 is provided with inward hollow projections 24 preferably struck therefrom. One important purpose formed by these projections is the prevention of rotative movement of the members 20 and 21 relatively to the filler member 25, the projections being seated in recesses in the ends of the filler member for this purpose. A shaft 27 extends through the drum and projects at both of its ends beyond said drum to provide journals 27'. Collars 27" are tightly fitted upon the projecting ends of this shaft and one of said collars bears at its inner end against the outer surface of the member 21 while the other collar bears at its inner end against the outer surface of a member 28 which is mounted upon the shaft 27. This member 28 is seated in the member 20 and is formed with a circular flange 28' having openings 28" arranged outside the member 20 and forming a gear. It is preferably formed of sheet metal stamped to shape. A simple means for assuring that it will be held against rotative movement relatively to the drum consists of a nail 29 driven through it and into the filler member 25.

Referring now to Figs. 9, 10 and 11, it will be seen that the drum C is mounted in a carrier comprising a top member 30 and end members 31 having at their lower ends outwardly turned flanges 32. The journals 27' of the drum are rotatively mounted in openings in the side members 31 of this carrier. Rods 33 extend through the openings in the flanges 32 and co-operate with said

flanges to guide the carrier in its up and down movements hereinafter more particularly set forth. 34 designates a shaft which forms an element of an operating means D. This shaft has its lower end provided with an inverted-crown gear 35, preferably formed of sheet metal struck to shape, whose teeth 35' engage the openings 28" of the member 28 to impart rotative movement to the drum C when the shaft 34 is rotated. This rotation of the drum, of course, is relatively to the arms 31 of the carrier and is for the purpose of bringing a selected stamping element into position to make an impression. The impression made by said stamping element is brought about by downward movement of the drum carrier. This movement of the drum carrier and drum is derived from longitudinal movement of the shaft 34 and is defined within limits which assures an unblurred impression by means hereinafter set forth. The upper end of the shaft is suitably secured to an operating handle 36 for convenience in operating it. It extends through a sleeve 37 the upper end of which extends into the open lower end of the handle 36. A spring 38 encircles the shaft 34 and has a fixed lower abutment 39 preferably provided by the inwardly turned lower end of the sleeve 37. This spring extends through the sleeve and into the upper end of the handle 36 and its upper end engages a collar or washer 40 which is fixed to the shaft.

Any suitable connection between the shaft 34, gear 35 and upper member 30 of the drum carrier capable of transmitting rotary movement to the gear 35 and drum relatively to the carrier from like movement of the shaft and also capable of transmitting longitudinal movement to the carrier and drum from longitudinal movement of the shaft, may be employed. As here shown the lower end of the shaft 34 is polygonal in cross section and extends through a correspondingly shaped opening in the gear 35 and a round opening in the top member 30 of the drum carrier, and a washer 41 is fixed on said lower end of the shaft above the top member 30 of the drum carrier. This construction permits the movements described.

Stop means are provided to define step-by-step rotative movements of the drum when moving the latter to bring a selected stamping element into position for use. The stop means here disclosed comprise a spring pressed plunger 42 adapted to enter the projections 24 in the end member 21. The spring 43 which operates this plunger, and the inner end of the plunger itself, are mounted in a sleeve 44 which projects inwardly from the adjacent arm 31 of the drum carrier. It will be apparent that the plunger 42 will snap into the projections 24,

the latter being cup-shaped, as shown, successively brought into operative relationship therewith by the rotative movements of the drum and will co-operate with said cup-shaped projections in holding the drum against accidental rotative movements from the position to which it has been set while yielding automatically to pressure brought about through the rotation of the shaft 34.

10 An indicating means is provided to indicate which stamping element is in position for use and hence to indicate when the desired stamping element has been brought to such position. The indicating means

15 consists of a pointer 45, which is rotated by the shaft 34, and a stationary dial. In the construction here shown, the pointer 45 is provided with a polygonal opening tightly receiving the similarly shaped lower end of

20 said shaft. This permits the shaft to move longitudinally relatively to the pointer while causing it to transmit its rotary movement to said pointer. The dial member of the indicating means embodies one of the

25 novel features of this invention. It includes a base member 46 and a face member 47 both formed of metal. The face member 47 is provided at intervals with openings 48 each of whose longitudinal walls is formed

30 with an upwardly extending flange 49. The openings in the face member correspond in number and position with the stamping elements on the drum and the flanges 49 terminate short of the front and rear ends of the

35 openings. In each of these openings an indicating member 50 having proper indicia thereon is arranged, the same resting on the upper surface of the base member and having its longitudinal edges underneath the flanges 49.

40 These indicators may be made of paper and each is separate from every other. It will be noted, therefore, that the indicating members may be interchanged readily it be-

45 ing only necessary to slip the one which is to be replaced out of its opening through the front of the latter and slip another one into place through said front. Obviously, these members will be held against accidental dis-

50 placement without being secured in position, by the portions of the face plate which overlap their edges. Simplicity of construction, inexpensive manufacture and the ease with which interchange of the indicat-

55 ing members may be made characterize this indicating means.

It will now be apparent that the construction illustrated permits any one of the series of stamping elements on the drum to be brought into position for use by rotation of the drum, and that the particular one which is in position for use will be indicated by the position of the pointer with relation to the indicating member 50 corresponding to said stamping element. It will also be

understood that interchange of the stamping elements and corresponding interchange of the indicating elements in expeditions and simple manner has been provided for in the construction herein set forth. 70

A suitable inking device is provided as a part of the stamp and this inking device should be free from contact with any of the stamping elements, except the one which is to make the impression and then only at a

75 time immediately preceding the moment at which the impression is made. I, therefore, have provided an inking means which comprises a frame E whose side members 51 are pivoted at their upper ends at 52, and have

80 their lower ends provided with a pan 53 containing an inking pad 54, which is normally out of contact with any of the stamping elements but in the path of downward movement of the latter, as indicated in Fig. 9. 85

Each side member 51 is provided with inwardly extending cam-shaped tracks 55 to be engaged by corresponding projections 56 carried by the side members 51 of the drum-carrier, the latter for this purpose being

90 shown as having a curved surface 57 beneath the said projection and normally out of contact therewith. In operation, the first portion of the downward movement of the drum-carrier will bring its portion 56 into

95 contact with the surface 55 of the frame of the inking means and further downward movement of said carrier will then cause it to turn the said frame of the inking means outwardly about the axis 52. By the said

100 first portion of the movement of the drum carrier the stamping element which is to make the impression is brought into contact with the inking pad and receives ink therefrom and then the inking pad is swung

105 outward from the path of movement of the drum to permit the stamping element to make its impression. This movement of the inking means is against the tension of a

110 spring 58 which is suitably arranged to return the inking means to its former position during upward movement of the carrier and drum. It will be understood that the down-

115 ward movement of the carrier and drum places the spring 58 of the operating means under tension adapted to cause the return of the carrier and drum to its raised position when pressure is removed from said operating means.

120 It is desirable in practice to enclose the operating mechanism in a casing so as to protect it and also protect the user against ink. I have shown, therefore, a casing which comprises a top member 59 which carries the stationary dial of the inking means hereinbefore referred to and also is provided with flanges 59' to which the frame E of the

125 inking means is pivoted. A separate member, open at top and bottom, marked F in the drawings, encloses the gearing and

70

130

stamping mechanism and has in its rear wall an opening 60 which is substantially closed by the frame E of the inking means when the latter is in position to apply ink to a stamping element, this opening 60 also affording provision for the swinging movements of said inking means. The bottom of the casing is provided by a plate G secured to the top member 58 by the rods 33, which rods as already set forth constitute, in connection with the flanges 32 of the drum-carrier, guides for such carrier in the up and down movements of the latter. The plate G has an opening through which the stamping element being used projects while making the impression and, of course, provides an extended and smooth bearing surface to engage the surface upon which the impression is to be made and thereby contributes to the production of an accurate and clear impression. To positively assure a clear and unblurred impression means are provided to stop the downward movement of the drum at the place at which the type member of the stamping element in use will have been brought into such contact with the surface to receive the impression that a blurred impression is not the result. In other words, it being understood that a blurred impression is the result of undue pressure of the type element against the surface which receives the impression and that great care must be exercised by the user to prevent such undue pressure, in hand stamps hitherto proposed, my invention contemplates as one of its features the provision of a positive stop which will act to prevent undue and harmful pressure of the type element against the surface which is to receive the impression, regardless of the pressure which is exerted by the user, thereby assuring a clear impression without calling for the exercise of any care whatever by the user. The means illustrated for this purpose comprise sleeves 61, 61 mounted on the guide rods 33 in position to be engaged by the flanges 32 of the drum carrier when the drum has been lowered to the position required to make the clear and unblurred impression referred to. It, of course, will be understood that as the drum is guided in its downward movement to traverse a vertical path that this guidance of the drum cooperates with the stop means in assuring a complete and unblurred impression.

One of the end walls of the casing is provided with an opening 62 in such relation to the drum that a stamping element may be slid longitudinally into or out of its receiving and retaining element B through said opening. This opening is preferably at the bottom of the casing, as shown, in position to be in line with one of the stamping elements or receiving elements B when the drum has been moved to its lowest po-

sition with reference to the bottom of the casing. The casing is provided with a bayonet shaped opening 63 to receive a projection 64 from the drum-carrier or with other suitable means, to hold the carrier and the drum in position against the tension of the spring 38 while the stamping elements are being inserted or removed. It will be understood that this insertion and removal of stamping elements can be most conveniently made when the stamp is in inverted position and that the receiving and retaining elements B may be successively supplied with stamping elements by turning the drum to bring them one after another into line with the opening 62, this movement of the drum being derived from intermittent rotative movement given the handle and being accomplished while the drum is held by the projection 64 and lateral portion of the bayonet slot 63, the gear 35 being in operative relationship with the teeth 28" of the drum gear in all positions of the drum longitudinally of the casing. The opening 62 has a prolonged upper wall 62' forming a guide and support upon which a stamping element may rest while being slid into or out of its receiving and retaining element B. In assembling these elements B to form the periphery of the drum, their lips 16 are first bent, as shown in Fig. 6, and slipped in this bent condition over the flange 22 of the end member 20, and after said element has been laid down to its place to span the space between said member 20 and the other end member 21, its lip 17 is bent around into holding relationship with the flange 23 of the latter.

Having thus described the invention what I believe to be new and desire to secure by Letters Patent, is:—

1. An interchangeable stamping element for a hand stamp, comprising a type member and a container member therefor, held together into a unitary structure, the container member having longitudinal marginal flanges and stop elements at one end of the stamping element and adjacent the flanges.

2. An interchangeable stamping element for a hand stamp, comprising a type member and a container member therefor, held together into a unitary structure, the container member having longitudinal marginal flanges and also having a bendable lip or flange projection from one of its ends and a stop at its other end.

3. An interchangeable stamping element for a hand stamp comprising a body member and a type member, the body member including a bottom and longitudinal side walls extending from said bottom and arranged inward of the longitudinal edges thereof to provide longitudinal marginal flanges extending outward from the lower ends of the side walls, and said type member

being arranged in the space between said side walls and firmly held to the body member.

4. An interchangeable stamping element for a hand stamp comprising a body member and a type member, the body member including a bottom and longitudinal and transverse flanges, the longitudinal flanges being at opposite sides of the member and arranged inward of the edges thereof and the transverse flange being at one end of the body member and extending with its ends outward beyond the longitudinal flanges, and said type member being arranged in the space partially bounded by said flanges.

5. An interchangeable stamping element for a hand stamp comprising a body member and a type member, the body member including a bottom and longitudinal and transverse flanges, the longitudinal flanges being at opposite sides of the member and arranged inward of the edges thereof and the transverse flange being at one end of the body member and extending with its ends outward beyond the longitudinal flanges, the body member also having bendable lips at its opposite ends, and said type member being arranged in the space partially bounded by said flanges.

30 6. An interchangeable stamping element for a hand stamp, comprising a body member and a type member, the body member having longitudinal flanges spaced from its opposite longitudinal edges to provide marginal flanges outward of said longitudinal flanges, the said longitudinal flanges receiving the type member between them and having their upper edges bent into a holding relationship with said type member.

40 7. An interchangeable stamping element for a hand stamp, comprising a body member and a type member, the body member having longitudinal flanges spaced from its opposite longitudinal edges to provide marginal flanges outward of said longitudinal flanges, the said longitudinal flanges receiving the type member between them and having their upper edges serrated and extending into the type member.

50 8. An interchangeable stamping element for a hand stamp, comprising a body member and a type member, the body member including a bottom and longitudinal and transverse flanges, the longitudinal flanges being at opposite sides of the member and arranged inward of the edges thereof and the transverse flange being at one end of the body member and comprising sections of different relative lengths, the larger section extending with its ends beyond the longitudinal flanges, said type member being arranged in the space partially bounded by the longitudinal and transverse flanges and the latter having their upper ends bent

into a holding relationship with said type member.

9. An interchangeable stamping element for a hand stamp, comprising a body member and a type member, the body member including a bottom and longitudinal and transverse flanges, the longitudinal flanges being at opposite sides of the member and arranged inward of the edges thereof and having serrated upper edges, and the transverse member being at one end of the body member and extending with its ends beyond the longitudinal flanges, said type member being arranged in the space partially bounded by the longitudinal and transverse flanges and said longitudinal flanges having their serrated edges extending into the type member.

10. An interchangeable stamping element for a hand stamp, comprising a body member and a type member, the body member including a bottom having an inwardly extending tip at one end, a transverse flange rising from its other end, and longitudinal flanges at its opposite sides arranged inward of the longitudinal edges of the bottom and of the opposite ends of the transverse flange, said type member being mounted in the space partially bounded by the transverse and longitudinal flanges.

11. An interchangeable stamping element for a hand stamp, comprising a body member and a type member, the body member including a bottom having an inwardly extending tip at one end, a transverse flange rising from its other end, and longitudinal flanges at its opposite sides arranged inward of the longitudinal edges of the bottom and of the opposite ends of the transverse flange, said type member being mounted in the space partially bounded by the transverse and longitudinal flanges, and said longitudinal and transverse flanges having their upper portions extending into a holding relationship with said type member.

12. In a hand stamp, a stamping element comprising a type member and a container member united to form a unitary structure, the container member provided with longitudinal marginal flanges, and a support for the stamping element, provided with a longitudinal groove into which the stamping element may be inserted or from which it may be removed by endwise movement, the support having ledges or flanges to overlie the marginal flanges of the stamping element.

13. In a hand stamp, a stamping element comprising a type member and a container member united to form a unitary structure, the container member provided with longitudinal marginal flanges, and a support for stamping element, provided with a longitudinal groove into which the stamping ele-

- ment may be inserted or from which it may be removed by endwise movement, the support having ledges or flanges to overlie the marginal flanges of the stamping element and said stamping element having means to define its longitudinal movement in one direction and releasable means to secure it against movement in the opposite direction, with relation to said support.
14. A hand stamp provided with a retainer member having longitudinal upwardly and inwardly extending flanges at its opposite sides, and a stamping member removably inserted therein and comprising a type member and a container member held together to form a unitary structure, the container member having longitudinal marginal flanges which underlie the inwardly extending flanges of the retainer member.
15. A hand stamp provided with a retainer member having longitudinal upwardly and inwardly extending flanges at its opposite sides, and a stamping member removably inserted therein and comprising a type member and a container member held together to form a unitary structure, the container member having longitudinal marginal flanges which underlie the inwardly extending flanges of the retainer member and also having a stop element at one end and a bendable holding lip or flange at its other end to hold it against longitudinal displacement in the retainer member.
16. In a hand stamp, a drum comprising end members having outwardly extending flanges and a series of retainers for stamping elements extending from one end member to the other and having their ends provided with lips or flanges bent into a holding relation with said flanges.
17. In a hand stamp, a drum comprising end members and a series of retainers for stamping elements, spanning the space between the end members and each having an open end and longitudinal ledges, in combination with a series of stamping elements insertible into and removable from the respective retainers by endwise movement of the stamping elements, each stamping element comprising a type member and container member therefor united to form a unitary structure, and said container member having longitudinal marginal flanges to underlie the ledges of the corresponding retainer.
18. In a hand stamp, a drum comprising end members and a series of retainers for stamping elements, spanning the space between the end members and each having an open end and longitudinal ledges in combination with a series of stamping elements insertible into and removable from the respective retainers by endwise movement of the stamping elements, each stamping element comprising a type member and contain-
- er member therefor united to form a unitary structure, and said container member having longitudinal marginal flanges to underlie the ledges of the corresponding retainer, each stamping element also having means to define its position within the retainer and hold it against longitudinal displacement in one direction when inserted thereinto and further having means to releasably secure its end to the support and to hold it against longitudinal displacement in the other direction.
19. In a hand stamp, a drum comprising end members, a series of stamp holders formed separately from the end members and spanning the space between the same and having their ends in a holding relation therewith, and a reinforcing member formed separately from the end members and stamp holders and secured in the space bounded by said end members and stamp holders.
20. In a hand stamp, a drum comprising end members having peripheral flanges, and a series of stamp holders formed separately from the end members and having their opposite ends provided with bendable lips which cooperate with said flanges in securing the holders in place.
21. In a hand stamp, a drum comprising end members having peripheral flanges each formed to provide a series of flat surfaces arranged successively thereabout, and a series of stamp holders formed separately from the end members and each having a bottom member whose ends rest upon corresponding flat surfaces of said flanges and are provided with bendable lips extending around the edges of the same.
22. In a hand stamp, a drum comprising end members, a series of stamp holders formed separately from the end members and spanning the space between the same, each stamp holder having at its opposite sides substantially right angular longitudinal flanges to provide channels which open laterally and have overhanging ledges, to receive and hold a stamping element, and means at the ends of the holders to hold them and the end members together.
23. In a hand stamp, a drum comprising end members, having peripheral flanges and a series of stamp holders formed separately from the end members and spanning the space between the same, each stamp holder having at its opposite sides substantially right angular longitudinal flanges to provide channels which open laterally and have overhanging ledges, to receive and hold a stamping element, each holder also having end lips co-operating with the flanges of the ends to hold the end members together.
24. In a hand stamp, a drum comprising end members, a series of stamp holders formed separately from the end members and spanning the space between the same,

and having their ends in a holding relation therewith, a reinforcing member formed separately from the end members and stamp holders and mounted in the space bounded by said end members and stamp holders, and means operatively related to the end members and the reinforcing member to prevent relative axial movement thereof.

25. In a hand stamp, a drum comprising 10 end members, a series of stamp holders formed separately from the end members and spanning the space between the same, and having their ends in a holding relation therewith, a reinforcing member formed 15 separately from the end members and stamp holders and mounted in the space bounded by said end members and stamp holders, said end members having projections extending into the reinforcing member and operative 20 to prevent relative axial movement thereof.

26. In a hand stamp, a drum comprising end members, a series of stamp holders formed separately from the end members and spanning the space between the same, 25 and having their ends in a holding relation therewith, a reinforcing member formed separately from the end members and stamp holders and mounted in the space bounded by said end members and stamp holders, said 30 end members having projections extending into the reinforcing member and operative to prevent relative axial movement thereof, the projections on one end member being substantially concave and open outwardly 35 and corresponding in number and location to the stamp holders to also constitute elements of a stop means.

27. In a hand stamp, a drum comprising 40 substantially cup shaped end members, a series of holders for stamping elements extending from one end member to the other and having lips at their ends operatively engaged with the peripheral portions of the end members, an internal reinforcing member, a substantially cup shaped member 45 mounted adjacent one of the end members and having its peripheral portion provided with gear teeth, means to secure the cup-shaped and reinforcing members together 50 against relative rotative movement, and journals projecting from the ends of the drum.

28. In a hand stamp, the combination of 55 a stamp support, series of stamping elements removably mounted thereon, means to move the support to place any one of the stamping elements into position for use, and means to indicate the stamping element which is in said position, including a relatively movable dial and pointer, the dial comprising a base 60 member and a face member, the face member having openings corresponding in number and position with the stamping elements and adjacent its said openings being spaced from the base member to receive the edges of indicators which are mounted on said base

plate and exposed through said openings, respectively.

29. In a hand stamp, the combination of a stamp support, a series of stamping elements removably mounted thereon, means 70 to move the support to place any one of the stamping elements into position for use, and means to indicate the stamping element which is in said position, including a relatively movable dial and pointer, the dial 75 comprising a base member and a face member, the face member having openings which correspond in number and position with the stamping elements and provided at opposite sides of each opening with flanges which extend upward and toward each other and terminate short of the ends of the openings, for the convenient insertion and removal of indicators into position to be exposed through 80 said openings, respectively.

30. In a hand stamp, the combination of a stamp support, a series of stamping elements removably mounted thereon, means including a rotative and longitudinally movable shaft operative by its rotative movement to 90 place any one of the stamping elements into position for use and by its longitudinal movement to move the support and stamping element to make the impression, and means to indicate the stamping element 95 which is in position for use, including a pointer partaking of the rotative movement of the shaft and relatively to which the shaft moves longitudinally, and a stationary dial, the dial comprising a base member and a 100 face member, the face member having openings corresponding in number and position with the stamping elements and having upwardly and inwardly extending walls which terminate at their front ends short of the 105 corresponding ends of the openings, to provide spaces adjacent the openings to receive the edges of indicators and to facilitate the insertion and removal of said indicators.

31. In a hand stamp, a stamping element; a support therefor; a longitudinally movable carrier for the support; operating means connected to the carrier to move the same; a casing including a bottom member having an opening through which the impression is made, a top member and rods connecting the bottom and top members to each other, the carrier having engagement with said rods to be guided thereby in its longitudinal movements in the casing; and stop elements mounted on the rods in the path of movement of the carrier in position to prevent the imposition of excessive pressure in the stamping element in making an impression, whereby smeared or blurred impressions are prevented regardless of the pressure exerted in the operating means.

32. In a hand stamp, a stamping element, a casing having an opening through which the stamping element may be inserted or re-

moved, and a support for the stamping element, mounted in the casing; the stamping element and support having means co-operating to permit the stamping element to be operatively engaged with and disengaged from the support, through the opening in the casing and by endwise movement of the stamping element.

33. In a hand stamp, a stamping element, a casing having an opening through which the stamping element may be inserted or removed, and a support for the stamping element, mounted in the casing; the stamping element and support having means co-operating to permit the stamping element to be operatively engaged with and disengaged from the support, through the opening in the casing and by endwise movement of the stamping element, said opening having a wall which is prolonged in the direction of the length of the stamping element and is substantially aligned with the stamping element to aid in the application or removal of the stamping element.
34. In a hand stamp, a stamping element, a support therefor, the stamping element and support having means co-operating to permit the stamping element to be operatively engaged with and disengaged from the support by endwise movement of the stamping element, a casing, an operating means to move the support and stamping element relatively to the casing, including a spring which is placed under tension by one movement of the support, the casing having an opening through which the stamp may be moved while being applied to or removed from the support, and co-operating means on the support and casing to hold the support in operative relationship with said opening against the tension of the spring while the stamping element is being applied or removed.

35. In a hand stamp, a stamping element, a support therefor, the stamping element and support having means co-operating to permit the stamping element to be operatively engaged with and disengaged from the support by endwise movement of the stamping element, a casing, an operating means to move the support and stamping element relatively to the casing, including a spring which is placed under tension by one movement of the support, the casing having an opening through which the stamp may be moved while being applied to or removed from the support, and also having a bayonet slot and the support having an element which traverses the slot and co-operates therewith to hold the support in operative relationship with said opening against the tension of the spring while the stamping element is being applied or removed.

36. In a hand stamp, a stamping element, a support therefor, the stamping element

and support having means co-operating to permit the stamping element to be operatively engaged with and disengaged from the support by endwise movement of the stamping element, a casing, and means to move the support and stamping element relatively to the casing in making the impression, the casing having an opening through which the surface of the stamping element projects in making the impression and also having a second opening adjacent the first mentioned opening and through which the stamping element may be applied to or removed from its said support.

37. In a hand stamp, a stamping element, a support therefor, the stamping element and support having means co-operating to permit the stamping element to be operatively engaged with and disengaged from the support by endwise movement of the stamping element, a casing, and means to move the support and stamping element relatively to the casing in making the impression, the casing having an opening through which the surface of the stamping element projects in making the impression and also having a second opening adjacent the first mentioned opening and through which the stamping element may be applied to or removed from its said support, the second opening having a wall which is prolonged in the direction of the length of the stamping element.

38. In a hand stamp, a stamping element, a support therefor, the stamping element and support having means co-operating to permit the stamping element to be operatively engaged with and disengaged from the support by endwise movement of the stamping element, a casing, and means to move the support and stamping element relatively to the casing in making the impression, the casing having an opening through which the surface of the stamping element projects in making the impression and also having a second opening adjacent the first mentioned opening and through which the stamping element may be applied to or removed from its said support, and co-operating means on the support and casing to hold the support in operative relation with the second opening while the stamping element is being applied or removed.

39. In a hand stamp, a longitudinally movable carrier, a drum rotatably mounted in said carrier, a series of stamping elements removably mounted about the surface of the drum, the drum and stamping elements being relatively formed to permit the latter to be severally applied to or removed from the drum, a casing having an opening through which the stamping elements may be so applied or removed, by endwise movement, and a rotative and longitudinally movable operating means having a connec-

tion with the carrier and a connection with the drum.

40. In a hand stamp, a longitudinally movable carrier, a drum rotatably mounted in said carrier, a series of stamping elements removably mounted about the surface of the drum, the drum and stamping elements being relatively formed to permit the latter to be severally applied to or removed from the drum by endwise movement of the stamping element, a casing having an opening through which the stamping elements may be so applied or removed; an operating means having a connection with the drum to rotate the same relatively to the carrier and also having a connection with the carrier to move the same longitudinally in opposite directions, the latter connection including a spring which is placed under tension in longitudinal movement of the carrier in one direction and thereby becomes operative to effect longitudinal movement of the carrier in the opposite direction, and means operative at will to hold the carrier against the latter movement and in operative relationship with said opening in the casing and to permit rotative movement of the drum.

41. In a hand stamp, a longitudinally movable carrier, a drum rotatably mounted in said carrier, a series of stamping ele-

ments removably mounted about the surface of the drum, the drum and stamping elements being relatively formed to permit the latter to be severally applied to or removed 35 from the drum by endwise movement of the stamping element, a casing having an opening in its bottom through which the impression is made, and having a second opening adjacent thereto through which the stamping elements may be applied to or removed from the drum, an operating means having a connection with the drum to rotate the same relatively to the carrier and also having a connection with the carrier 45 to move the same and the drum longitudinally in opposite directions the latter connection including a spring which is placed under tension in longitudinal movement of the carrier in one direction and thereby becomes operative to effect longitudinal movement of the carrier in the opposite direction, and means operative at will to hold the carrier against the latter movement and in operative relationship with the openings 50 in the casing and permits rotative movements of the drum for the convenient application or removal of any one or more stamping elements.

In testimony whereof I affix my signature.

GEORGE G. MEVI.
